STRUCTURE HAVING A FOLDING SUPPORT SURFACE

Harold Howe, Rowayton, Conn.

Application April 24, 1942, Serial No. 440,343

15 Claims. (Cl. 311—90)

This invention relates to folding support structures, such as tables, chairs, ironing boards and the like.

An object of the invention is to provide a folding top or supporting surface provided with support means including connecting links so correlated to the top or other support surface that the act of folding together the hinged portions of the top or other support surface causes collapsing or folding of said support means.

Another object of the invention is to provide a folding top or support surface having collapsible support means which is simple and durable and will give firm and dependable support in use, without danger of being collapsed inadvertently.

Another object of the invention is to provide a folding top or other supporting surface having folding support means adapted, when the structure is folded, to lie substantially in the planes of the folded portions of the top.

Another object of the invention is to provide in combination a supporting surface, comprising a plurality of portions hinged together, and support means for said portions respectively including link means, between the support means of one of said portions and the other of said portions, adapted, when a folding force is exerted on the portion of said supporting surface to which said link is connected to transmit said force to the support means to which said link is connected.

Another object of the invention is to provide linkage between the foldable support means of one portion of a foldable supporting surface, comprising a plurality of portions hinged together, and the other portion of said supporting surface.

Another object of the invention is to provide connecting means, between the legs of one portion of a foldable table or other supporting surface comprising a plurality of portions hinged together and the other portion of the table or other supporting surface, beyond the line of division between said portions.

Another object of the invention is to provide a connecting link between one portion of a table top or other supporting surface, comprising a plurality of portions hinged together, and the support means for the other portion of said table top or other supporting surface, said link being related to said support means and to said table portion so as to provide a lock against inadvertent folding of said structure.

Another object is to provide, in the kind of device described, in combination with the foldable legs thereof, handle means adapted to be

projected for use when the structure is folded and to be withdrawn within the device when it is unfolded.

Another object is to provide in the kind of device described, folding means related to the folding leg structure in such a way that said means will be collapsed when the folding legs are collapsed and will be extended in a direction substantially opposite to the legs when the folding legs are extended.

Other objects will be in part obvious or in part pointed out hereinafter.

In the accompanying drawings:

Fig. 1 is a view in perspective showing the under side of a folding table embodying my invention;

Fig. 2 is a side transverse sectional view of the structure shown in Fig. 1 unfolded for use;

Fig. 3 is a view similar to Fig. 2 showing the table partly folded;

Fig. 4 is a perspective view showing the table completely folded;

Fig. 5 is a side transverse sectional view of a modification of the structure shown in Figs. 1-4;

Fig. 6 is a side transverse sectional view showing more or less diagrammatically disposition of the parts to provide a lock for the structure in extended position;

Fig. 7 is a side transverse sectional view of another modification of the structure shown in Figs. 1-4;

Fig. 8 is a side transverse sectional view of another modification of the structure shown in Figs. 1-4, showing two-part support legs;

Fig. 9 is a side transverse sectional view of a supporting surface similar to the embodiment of the invention shown in Figs. 1 to 4 with added members adapted to be projected upwardly when the structure is unfolded.

In the embodiment of the invention shown in Figs. 1 to 4 inclusive a supporting surface is shown divided along its transverse median line into the portions 10 and 11 hinged together by the hinges 12—12' which may be secured on the bottom surface of flanges 13 and 13' respectively extending downwardly from the end edges of the two portions 10 and 11. The portions 10 and 11 may be moved on their hinges 12—12' from the unfolded position of Fig. 1 in which the edges of the portions are in abutting relation, to the position of Fig. 4 in which the two portions are superimposed one on the other so that they lie in adjacent parallel planes.

In the embodiment of the invention shown in Figs. 1-4 the support means for support surface

portions 10 and 11 are similar. As illustrated herein the support means for portion 10 comprises the legs 14 joined together by the cross member 15 which is pivotally mounted by the pivots 16 on the cross bar 17 the ends of which are slidably seated in the slideways 18 provided in the inner faces of the side flanges 13a projecting downward from the side edges of the supporting surface portion 10.

Extending between the support means and the portion of the supporting surface on which the support means is mounted, links 19 are respectively pivotally secured at one end, by the pivots 20 to the legs 14 respectively, and are pivotally secured respectively at the other end by the pivots 21, to the portion 10 of the supporting surface, preferably by connection to the lugs 22 respectively projecting inwardly from the side of the inner end flange 13 of supporting surface portion 10. Extending between the support means and the portion of the supporting surface which is across the hinged connection between the supporting surface portions, link 23 is pivotally secured at one end, by pivot 24, to the cross bar 17, and is pivotally secured at its other end, by pivot 25, to the portion 11 of the supporting surface, preferably by connection to a lug or finger 26 projecting inwardly from the side of the inner end flange 13' of the supporting surface portion 11.

In the embodiment of the invention in Figs. 1-4 the pivotal connection 24 of link 23 is positioned closer to the under surface of portion 10 of the supporting surface than the connections 20 between links 19 and legs 14 respectively. The pivot connection 25 of link 23 is preferably closer to the under surface of portion 11 of the supporting surface than the hinge pins of hinges 12 and 12' relative to the under surfaces of portions 10 and 11 respectively. The table portions 10 and 11 turn on a shorter radius than link 23 and thus, until link 23 moves past the plane containing the said hinge pins, a pull is exerted on the link 23 toward the pivot 25. Since the cross rod 17 is at the inner limit of slideway 18 when the structure is completely unfolded the cross rod 17 itself has to bow out slightly, from its normal straight line position, and the force necessary to bow out cross rod 17 is the approximate measure of the locking effect obtained resisting inadvertent folding of the structure.

The support and link means for the supporting surface portion 11 are similar to those described in connection with supporting surface portion 10. The legs 14' are joined together by the cross member 15' which is pivotally mounted by the pivots 16' on the cross bar 17' the ends of which are slidably seated in the slideways 18' provided in the inner faces of the side flanges 13a' which project downwardly from the side edges of the supporting surface portion 11. The legs 14' are set closer together than the legs 14 so that when the structure is folded the legs 14' will lie between the legs 14. Links 19' are respectively pivotally secured at one end by the pivots 20' to legs 14' respectively and are pivotally secured respectively at the other end, by the pivots 21' to the portion 11 of the supporting surface, preferably by connection to the lugs 22' respectively projecting inwardly from the side of the end flanges 13' of surface portion 11. Extending between the support means for portion 11 of the supporting surface and portion 10 of the supporting surface link 23' is pivotally secured at one end, by pivot 24' to the

cross bar 17', and extends beyond the line of division between portions 10 and 11 and is pivotally secured at its other end, by pivot 25' to the portion 10 of the supporting surface, preferably by connection to a lug or finger 26' projecting inwardly from the side of the end flange 13 of the supporting surface portion 10.

The relative spacing of pivot point 24' and pivot points 20' from the under surface of portion 11 of the supporting surface, and the relative spacing of pivot point 25' and the hinge pin points of hinges 12 and 12' from the under surface of portions 10 and 11 respectively of the supporting surfaces, preferably correspond with the spacing of the similar points described above in connection with the support and link means for portion 10 of the supporting surface.

Also pivotally secured to cross bar 17 by pivots 27 are the ends of a bail or U-shaped handle 28 the arms, a, of which are inserted through, and are slideable in, bores, b, extending through the outer end flange 13 of supporting surface portion 10.

When the device shown in Figs. 1-4 is in unfolded position it will be seen that the links 23 and 23' transmit to one portion of said supporting surface any force exerted on the support means for the other portion of said supporting surface tending to collapse said support means in synchronized relationship thus giving great strength and rigidity to the supporting surface when in use, and making separate locks unnecessary.

It will also be seen that when it is desired to fold the structure the rotation of one of the portions 10 and 11 of the supporting surface toward one another on hinges 12-12' causes the links 23 and 23' respectively to exert pressure outwardly on the upper end of the respective support means, causing cross bars 17 and 17' respectively to slide outwardly, away from the line of division between the supporting surface portions, in slideways 18 and 18' respectively. Since the links 19 and 19' respectively connect the support means respectively by fixed pivots to the same portions 10 or 11 of the supporting surfaces to which they are also slidably connected the force exerted through links 23 and 23' will, after overcoming the slight toggle lock referred to above, cause the support means to be collapsed i. e. moved from an unfolded position such as is shown in Fig. 2 to a folded position such as is shown in Fig. 4, after passing through the intermediate folding stage indicated in Fig. 3.

For convenience a small catch or lock, such as a pin and hook combination indicated at 29, may be used to hold the portions 10 and 11 of the supporting surface together in folded position.

In Fig. 5 an embodiment of the invention is shown which is similar to that shown in Figs. 1-4 except that the support means for the hinged together supporting surface portions 10 and 11 are pivotally secured to links which are connected by fixed pivots to the said respective supporting surface portions. Thus leg 14 for supporting surface portion 10 is pivotally secured to the link 31 by pivot 32, and the other end of link 31 is connected to portion 10, preferably through side flange 13a, by the fixed pivot 33. And the connecting link 23 is secured at one end to the pivot 32, which may be a rod extending between a pair of legs for support surface portion 10, and is secured at its other end by pivot 25 to a finger 26 projecting inwardly from the downwardly ex-

tending flange 13' on portion 11 of the support surface.

When the modification of Fig. 5 is folded link or links 31, as the case may be, are swung outwardly around the fixed pivot or pivots 33 under the impulse of connecting link 23 carrying the upper end of leg or legs 14 outwardly while the leg or legs rotate into parallelism with the support surface portion 10 around the pivot or pivots 20 of link or links 19.

In Fig. 6 I have illustrated diagrammatically in connection with the embodiment of the invention shown in Figs. 1 to 4 the locking action which I may provide by links 23 if the pivot 25 of link 23 is positioned closer to the under surface of the unfolded structure than the hinge pins of hinges 12-12'. As illustrated in Fig. 6 link 23 extends through upwardly extending cut outs 41 in inner flanges 13 and 13' of supporting surface portions 10 and 11 respectively so that pivot 25 is closer to the under surface of the unfolded support surface than the hinge pins of hinges 12-12'. As pivot 25 moves from the position shown in full lines to the position shown in dotted lines it will tend to move in the direction indicated by the arrow 41. This is because table portion 11 in turning around the hinge pins of hinges 12-12' is moving on a shorter radius than link 23 rotating around pivot 24. Consequently pivot 24 will have to move from the position shown in full lines to the position shown in dotted lines, until pivot 25 reaches the position shown in dotted lines after which the pull on link 23 will cease and a thrust will be exerted in the opposite direction, as supporting surface portion 11 rotates further toward folded position, causing cross bar 17 to move outwardly in slide ways 18. It will be understood that the same principle may be applied in any of the embodiments shown herein to obtain a locking action initially resisting folding of the support surface.

Fig. 7 shows another modification of the invention which differs from the embodiment of the invention shown in Figs. 1-4 chiefly in that the support means are attached to the support surface portions on fixed pivots; the link between a support means and a portion of the support surface supported thereby comprises two parts pivoted together, and the link between one support means and the portion of the supporting surface beyond the line of fold is connected to the pivot of said two-part link means.

As illustrated the supporting surface comprises the portions 10 and 11. The leg 14 is pivotally connected to cross bar 17 which is fixedly mounted between the depending flanges 13a of portion 10 of the supporting surface. The link means between the portion 10 and leg 14 comprises the parts 49a and 49b pivotally hinged together by the pivot 52. The other end of link member 49a is pivotally supported on the under side of supporting surface portion 10 on pivot 51, and the link member 49b is pivotally connected at its other end to pivot 52. The connecting link 23 is pivotally connected at one end to the pivot 50 on which link members 49a and 49b are pivoted, and, after extending beyond the line of division between portions 10 and 11, is secured at its other end to the pivot 25 supported by finger 26 projecting inwardly from the downwardly projecting inner flange member 13' of supporting surface portion 11.

It will be understood that as the support surface portions 10 and 11 are folded together pivot 50 is caused to move outwardly due to the im-

pulse transmitted to it by link 23 thus collapsing link members 49a and 49b and drawing the lower end of leg 14 inwardly until it lies within the supporting surface portions 10 and 11 when they are folded together.

In Fig. 8 another modification of the invention is shown employing a two-part support means or legs. As illustrated the support means for support surface portion 10 comprises the members 44a and 44b pivoted together on the pivot 45. The support means itself is pivotally mounted on pivot 17 which may be a cross bar extending between the downwardly extending side flanges 13a of the support surface portion 10. Link member 23 is connected between pivot 45 and pivot 25 supported by finger 26 extending inwardly from the downwardly projecting end flange 13' of the portion 11 and thus spanning the line of division between the two table portions 10 and 11. Link 19 is pivotally connected at one end to the pivot 21 supported by bracket 22 secured to the inside of the depending end 13 of support surface portion 10 and connected at its other end by pivot 46 to the lower leg portion 44b.

The leg portions 44a and 44b may of course be related in a number of different ways, and if desired may be formed of three-sided angle members so that one portion is foldable within the other portion.

As the support surface portions 10 and 11 are folded together the impulse delivered by link member 23 on pivot bar 45 causes the leg members 44a and 44b to be collapsed as shown in dotted lines.

The embodiment of the invention shown in Fig. 9 is similar to that illustrated in Figs. 1-4 inclusive with the addition of means adapted to be projected upwardly from the supporting surface when the structure is unfolded and to be collapsed into substantial parallelism with the folded portions of the structure. As illustrated the structure comprises the supporting surface portions 10 and 11 and has a support means 14 pivotally mounted on the pivot 17 the ends of which are slideable within slide ways 18 provided in the downwardly extending flanges 13a of support surface portion 10. Link 23 extends between the pivot rod 17 and the pivot 25 supported by finger 26 extending inwardly from the depending end flange 13a of portion 11, beyond the line of division between portions 10 and 11. Link member 50 is secured to leg 14 by pivot 51 and is connected at its other end to pivot 52 which may be a rod between the downwardly depending flanges 13a of support surface portion 10.

Also fixed to pivot 17 and extending upwardly with relation to the support surface portion 10 when it is in unfolded position is a member 53 and extending upwardly from pivot 52 in similar manner is member 54a-b. Also fixed at one end of pivot 52 is a member 55 the other end of which is connected to member 53 by pivot 56. Preferably support surface portion 10 is slotted to permit the passage therethrough of members 52, 53, and 55 but it would of course be possible to have these members bent around the side edges of support surface portion 10. Members 54a and 54b are pivoted together by pivot 54, the lower end of 54b being attached to member 53 by pivot 52. A member 57 is pivoted to the upper end of member 54a by pivot 58, and the other end of member 57 is pivoted to member 53 by pivot 59.

When table portions 10 and 11 are folded toward one another connecting rod 17 will slide rearwardly in the slideway 18 carrying with it the upper end of leg members 14 and the lower end of member 53 thus causing members 53, 54a-b, 55, and 51 to be collapsed into substantial parallelism to the upper surface of portion 10 while leg 14 is moving into substantial parallelism to support surface portion 10.

As there are many possible embodiments of the above invention and as many changes might be made in the embodiments set forth above the accompanying drawings are to be interpreted as illustrative and not in a limiting sense.

I claim:

1. In a device of the kind described the combination of a top or other supporting surface comprising a plurality of portions hinged together, support means for said portions slidably connected to the under side of said portions respectively, and a connecting link between each of said portions respectively and the support means for the other of said portions, said connecting link being pivotally connected to said support means adjacent the said sliding connection between the said support means and said top or supporting surface portion whereby, as the said portions are moved from abutting relation to superimposed relation, the upper end of said support means is moved away from the hinged connection between said portions, and connecting means, pivoted at one end to said support means below its connection to said connecting link and pivoted at its other end to said portion supported by said support means, whereby, as the upper end of said support means slides outwardly along its slideway in said portion, the lower end of said support means will move in toward the said hinged connection between the top portions.

2. In a device of the kind described the combination of a top or other supporting surface comprising a plurality of portions hinged together, support means for said portions, slidably connected to the under side of said portions respectively, and a connecting link between each of said portions respectively and the support means for the other of said portions, said connecting link being pivotally connected to said support means adjacent the said sliding connection between the said support means and said top or supporting surface portion and connecting means pivoted at one end to said support means below its connection to said connecting link and pivoted at its other end to said portion supported by said support means, and a handle member, slidably supported under one of said top portions and having extended arms pivotally secured to said support means adjacent its upper end, adapted to be projected beyond the end of said top portion when the said device is folded and to be withdrawn beneath the top portion when the device is in unfolded position.

3. In a device of the kind described the combination of a top or other supporting surface comprising a plurality of portions hinged together, support means for said portions, slidably connected to said portions respectively, and a connecting link between each of said portions respectively and the support means for the other of said portions, said connecting link being pivotally connected to said support means and said supporting surface portion, and connecting means pivoted at one end to said support means below its connection to said connecting link and

pivoted at its other end to said portion supported by said support means, a member pivotally connected at its lower end to said support means adjacent its upper end, and means pivotally connected between said member intermediate its ends and the respective top portion for said support means whereby said member is collapsed when said support means is collapsed and is raised into angular relation to said top portion when said support means is unfolded.

4. In a device of the kind described in combination a supporting surface comprising a plurality of portions hinged together, support means for each of said portions the upper ends of said support means being mounted respectively in slideways extending lengthwise of said portions, connection links pivotally connected at both ends between said portions respectively and the support means for the other portion adjacent the said slideably mounted end of said support means, brace members pivotally connected at one end to one of the support means respectively, and pivotally connected at the other end to the portion of said supporting surface on which said support means is slideably mounted, a member associated at one end with the slideable upper end of one of said support members so as to be slideable therewith, said member projecting upwardly relative to said supporting surface, when the latter is extended, in a direction opposite to the support member with which it is associated, and a brace member pivotally secured at one end to said member intermediate its ends and pivotally connected at its other end to the same supporting surface portion to which said member is connected.

5. In a device of the kind described in combination a supporting surface comprising a plurality of portions hinged together, support means for each of said portions the upper ends of said support means being mounted respectively in slideways extending lengthwise of said portions, connection links pivotally connected at both ends between each of said portions respectively and the support means for the other portion, brace members each pivotally connected at one end to one of the support means for one of said portions respectively and pivotally connected at the other end to the portion of said supporting surface on which said support means is slideably mounted, a member associated at one end with the slideable upper end of one of said support members so as to be slideable therewith and adapted to be projected upwardly from said supporting surface when said surface is unfolded, and a brace member pivotally secured at one end to said member intermediate its ends and pivotally connected at its other end to the same supporting surface portion to which said member is connected, and two links pivotally joined together at one extremity of each, the other ends of said links being pivotally joined respectively to said member intermediate its ends and to the said supporting surface portion to which said member is connected.

6. In a table having a top divided transversely into two portions hinged together so that it is foldable along its median transverse line from a position in a single plane into a position in two parallel planes, the combination of, support means for said table top portions respectively each spaced from said median line and movable from a folded position substantially parallel to the table top to an extended position angularly disposed with relation to the table top, and con-

necting link means interposed between each support means and the table top portion on the opposite side of said median transverse line from said support means so that when the table top is folded said link means will exert a thrust, on said support means and when the table top is unfolded said link means will exert a pull on said support means.

7. A folding table comprising a top divided transversely into two portions hinged together, leg support means for said portions respectively, each of said leg support means being movable from a position substantially normal to its table top portion to a collapsed position substantially parallel to said table top portion, and means interconnecting each of said leg support means respectively and the table top portion other than the portion supported by the leg support means to which said interconnecting means is secured, so that as the table portions are folded together or unfolded said interconnecting means serve to move said leg support means respectively from extended to collapsed position or vice versa.

8. A folding table comprising a top divided transversely along its median line into two portions hinged together, a pair of legs for each portion, the legs of each pair respectively being slideably secured at their upper ends to one of said portions for movement in a plane parallel to the surface of said portion, link members pivotally secured at one end to said legs respectively and at the other end to the same table top portion as the legs to which they are respectively secured, cross members joining the legs of each pair of legs respectively, and other link members for said pairs of legs respectively, each pivotally secured at one end to one of said cross members and pivotally secured at its other end to the table portion across said line of fold of said table from the said cross member to which it is secured.

9. A folding table comprising a top divided along its transverse median line into two portions, means for hingedly joining the two portions so that the structure may assume alternately an extended position in which the two portions are in abutting relation in the same plane and a folded position in which the two portions are in adjacent parallel planes, flanges extending downwardly around the periphery of each of said portions, support means for each portion of said table including slideways in the said flanges and means for keying the upper end of said support means in the said slideways so that said support means may be moved from an upright position substantially at right angles to the table top portion to a collapsed position substantially parallel with the table top portion, connecting link means pivotally secured at one end to said support means and, at its other end, to the under surface of the same table top portion on which said support means is mounted, and other connecting link means pivotally secured to the said support means at one end and pivotally secured at its other end beyond said transverse median line beneath the other of said table top portions.

10. A folding supporting surface divided along its transverse median line into two portions, means for hingedly joining the two portions, for movement from abutting to superimposed position and vice versa support means pivotally connected at the upper end to each of said portions respectively, folding braces for each of said support means comprising two members hinged together adjacent one end of each, the other end of one of said members being pivotally connected

to said support means, and the other end of the other of said members being pivotally connected to the said portion to which said support means is connected, and link means pivotally connected at one end to the point of connection between the members comprising a folding brace and pivotally connected at its other end to the supporting surface portion beyond the said median line from the said folding brace.

11. In a folding structure of the kind described including, a supporting surface divided transversely along its median line into two portions hinged together, collapsible support means for each of said supporting surface portions and members interconnecting the said support means to each of said supporting surface portions respectively, a multi-bar-linkage comprising collapsible support means linkage and operating linkage having one or more links in common.

12. A support surface comprising two centrally hinged sections, support legs connected to each section, a link means pivotally connected between said legs and their sections respectively, connecting rods pivotally connected between the support legs of each section respectively and the other section beyond the line of centrally located hinge points, so that in folding two sections together the lower ends of said legs fold toward the center in synchronous action.

13. In a folding structure of the kind described a five-bar-linkage member comprising, one of two hinged together portions of a supporting surface, a part of the other portion of said supporting surface, foldable support means pivotally joined to said first mentioned supporting surface portion, a connecting member, operative at all times including when the structure is being folded and unfolded, extending from said other supporting surface portion to said foldable support means, and connecting means extending between said foldable support means and said first mentioned supporting surface portion.

14. In a device of the kind described, a top or other supporting surface comprising a plurality of portions each of said portions having a downwardly projecting flange along one edge, and hinge means interconnecting the said flanges of said portions, collapsible support means for said portions respectively, and resilient link means pivotally connected at one end to the support means of one of said portions and extending across the hinged-together downwardly depending flanges and pivotally secured at the other end to the table portion across said hinged line of fold from the said cross member to which it is secured, the said hinges interconnecting the downwardly extending flanges of said portions being positioned below the top or other supporting surface sufficiently so that the said hinges lie below an imaginary plane containing both the pivotal connection of said link means to the support means of one of said portions and its pivotal connection to the other of said table top portions, so that when the device is in fully extended position the link means will be slightly bowed downwardly around the said hinged-together downwardly depending flanges of said portions and will therefore tend to straighten and to thus initiate the folding action of the device when it is lifted preparatory to folding.

15. In a folding table comprising a top divided into a plurality of portions joined together by hinge means, and leg support means for said portions respectively, movable from a position substantially normal to its table top portion to a col-

apsed position substantially parallel to said table top portion, and link means pivotally connected at one end to one of said leg support means and pivotally connected at its other end to the table top portion other than the portion supported by the said leg support means to which said interconnecting means is secured, said table top portions each having depending flanges along their abutting edges serving to support said hinge means at a distance below said table top, and the said pivotal connection between said interconnecting means and said top portion being positioned closer to the undersurface of said table

top than the hinge pins of said hinge means, whereby, when folding of the table is initiated, and when opening of the table is almost complete, the interconnecting means will tend, momentarily, to move horizontally in a direction across the said hinge means from the said leg support means to which said interconnecting means is connected, due to the different radii on which said top portion and said interconnecting means are moving, thus providing means resisting inadvertent folding of the table structure.

HAROLD HOWE.
